FIG. 1.

FIG. 3.

UNITED STATES PATENT OFFICE

2,413,939

ULTRA HIGH FREQUENCY DISCRIMINATOR

Robert T. Benware, Philadelphia, Pa., assignor to
Philco Corporation, Philadelphia, Pa., a corporation of Pennsylvania

Application March 21, 1944, Serial No. 527,442

3 Claims. (Cl. 250—27)

1

This invention relates to frequency variation response circuits, and particularly to those circuits which are responsive to frequency variation in the range of frequencies generally referred to as "microwaves."

While no definite frequency limits are associated with the term "microwaves," this term is sometimes used to identify radio waves whose length may be from less than 1 centimeter to 30 centimeters, or whose frequencies may be from about 1000 megacycles to more than 30,000 megacycles.

At these very high frequencies, often referred to as hyper-frequencies, energy may be transmitted, radiated or received by means of hollow pipe conductors, or wave guides, instead of by the conventional transmission lines and antennae. The principles of operation and the structure of wave guides and resonant chambers are now generally understood by those skilled in the art, and considerable information has been published in technical periodicals and in books, such as "Hyper and Ultra-High Frequency Engineering," by Sarbacher and Edson, published in 1943 by John Wiley and Sons. Therefore, it is unnecessary to discuss here the theory and constructional details of such devices.

It is an object of the present invention to provide, by means of a novel system of hollow wave guides, or resonant cavities, a high frequency circuit that is responsive to the frequency deviations of frequency-modulated radio waves.

Another object of the present invention is to provide a frequency discriminator or frequency detector circuit for use at hyper frequencies.

Other objects and advantages of the present invention will become apparent during the course of the following description with reference to the associated drawing, in which:

Fig. 1 is an exploded isometric illustration of one embodiment of the wave guide assembly which forms a part of the circuit of this invention;

Fig. 2 illustrates schematically a frequency discriminator circuit constructed in accordance with the present invention; and

Fig. 3 is a typical response curve for the circuit of this invention showing output voltage plotted against applied frequency.

Referring to Fig. 1, the hollow rectangular wave guide, or cavity, 11, which may be considered as the primary wave guide or primary circuit of the system, is arranged to receive electromagnetic energy at its open end 12. The opposite end of this wave guide is provided with an adjustable tuning means which may comprise a movable baffle or piston 13 of conducting material. For

2

clarity, this baffle is shown exterior to the wave guide. Attached to each face or broad side of the primary wave guide 11 is another section of wave guide, as indicated at 14 and 15. These two latter wave guides, constituting secondary circuits of the system, are also fitted with adjustable tuning means, such as the baffles 16 and 17. For the transfer of electromagnetic wave energy from the primary wave guide 11 into the secondary guides 14 and 15 a suitable opening may be located in each face of guide 11, as indicated in the drawing at 18 and 19.

Fig. 2 is a cross-sectional view of the wave guide, or cavity, assembly taken in a plane containing the longitudinal axes of the primary and secondary wave guides. In this figure the relative positions of the movable pistons in the wave guides are shown, and in addition the location of the coupling probes or loops and the detectors is indicated. The corresponding parts of Fig. 1 bear the same identification in Fig. 2. The primary wave guide, its open receiving end and its movable piston in an arbitrary position are indicated at 11, 12 and 13 respectively. The secondary wave guides with their baffles are shown at 14, 15, 16 and 17. The energy coupling holes or irises are shown at 18 and 19. The secondary wave guides 14 and 15 are each equipped with a conventional probe and detector assembly 20 and 21 respectively. Each detector assembly may comprise a pick-up loop, one end of which is fastened to the wave guide and the other end of which is connected to one terminal of a detecting device which, in the preferred embodiment, is a cartridge type crystal detector. The pick-up loops are illustrated at 22 and 23, while 24 and 25 represent the crystal detectors. The detector assemblies 20 and 21 are equipped with some conventional form of by-pass circuits to permit the maximum available high frequency voltage to be applied across detectors 24 and 25. In the embodiment shown in Fig. 2 the elements 35 and 36, known in the art as quarter wave chokes, form with their respective walls 37 and 38 of the detector assemblies, high frequency by-pass circuits. Elements 35 and 36 may be hollow structures of conducting material, closed at the end adjacent to the crystal detectors 24 and 25. Structures 35 and 36 are mounted within and insulated from the walls 37 and 38 so as to form with these walls open circuited quarter wave sections of transmission lines. The free terminals of detectors 24 and 25 are connected to the closed end of elements 35 and 36. Since the structures 35 and 36 form, with walls 37 and 38, open circuited quarter wave sections of a transmission

line, the impedance between the output terminals of detectors 24 and 25 and the walls 37 and 38 is substantially zero for high frequency currents and infinite for the rectified currents.

Two detector load resistors 26 and 27, preferably of equal value, are serially connected between the crystal elements 24 and 25. The common terminal or junction 28 of the two resistors is electrically connected to the wave guide at some point 29 by conductor 30. The position of this point is, in general, not critical, since the conductor 30 carries low frequency currents only. The other end 31 of resistor 26 is connected to the free terminal of crystal detector 24 by conductor 32, while the other end 33 of resistor 27 is connected by conductor 34 to the free terminal of crystal detector 25.

The operation of this invention as a frequency discriminator or detector of frequency-modulated radio waves will now be described with reference to Fig. 2 and for the TE₁₀ mode of propagation, in which the electric field vector is perpendicular to the broad sides of the wave guides.

The electromagnetic energy is received by and transmitted through wave guide 11. Since this primary wave guide is terminated in a conducting baffle 13 the incoming electromagnetic wave is reflected by this plate. The reflected wave combines with the incoming wave to form in guide 11 a standing wave in which the electric and magnetic components are in phase quadrature. The electric field is short circuited by the baffle 13 and accordingly at regions an integral number of half wave lengths from the baffle the electric field intensity is minimum and the magnetic field is at maximum intensity. The secondary wave guides 14 and 15 and coupling irises 18 and 19 are located at a distance which is an integral number of half wave lengths from the baffle 13, that is, at regions of high magnetic field intensity. The secondary guides 14 and 15 may then be considered as inductively coupled to the primary guide 11.

The Q, or sharpness of resonance, of the wave guide 11 is affected by the amount of energy coupled into the secondary guides 14 and 15 from the primary circuit 11. This is analogous to the conventional tuned circuit of lumped inductance and capacity in which the Q or resonant property of the tuned circuit is lowered by the coupling of a secondary circuit to the tuned circuit.

In the circuit of this invention the primary wave guide 11 is tuned by means of sliding piston 13 to the mean or carrier frequency of the frequency modulated radio wave. The magnitude of coupling between the primary circuit 11 and the two secondary circuits 14 and 15 is preferably such as to cause the primary wave guide 11 to be resonant with a fairly low Q.

The secondary wave guides 14 and 15 are also terminated by short circuiting pistons 16 and 17 to form resonant chambers. The movable pistons 16 and 17 are likewise located at distances an integral number of half wave lengths from the coupling holes 18 and 19, thereby forming standing waves of high magnetic field intensity in the vicinity of the pistons 16 and 17. The pick-up wires or coupling probes 22 and 23 are accordingly in regions of high magnetic field intensity. The high frequency voltage induced in loop 22 is impressed directly across crystal detector 24, the capacitive reactance between the $\frac{1}{4}$ -wave length choke and the cylindrical conductor being negligible at the carrier frequency.

The rectified output current of the crystal flows through the detector load resistor 26, producing an output voltage across this resistor. Likewise, the voltage induced in loop 23, due to the varying magnetic field in chamber 15, is impressed across crystal detector 25 to develop across resistor 27 a rectified output voltage.

The secondary wave guides 14 and 15 are so tuned by their respective movable pistons 16 and 17 that one secondary circuit is resonant to a frequency on one side of the carrier frequency while the other secondary is tuned to a frequency on the other side of the carrier.

To insure good linearity in the overall response of the discriminator system, it is preferred that the effective Q's of the two secondary circuits be relatively high compared to the Q of the primary circuit. Where such relatively high secondary Q's are desired it is best not to couple the detector circuits too tightly to the secondary wave guides. In Fig. 2 the small coupling loops or probes 22 and 23 provide only moderate coupling, and were found to be quite satisfactory.

The frequency discriminating action of the circuit of this invention as shown in Fig. 2 may be described as follows.

Assume that the received carrier wave of normal frequency f_0 is frequency modulated so as to vary it from a frequency of f_1 below f_0 to a frequency f_2 above f_0 , such that $f_0 - f_1$ equals $f_2 - f_0$. The wave guide 11 is tuned by movable piston 13 to the carrier frequency f_0 and the secondary wave guide 14 is tuned by piston 16 to frequency f_1 while the other secondary wave guide 15 is tuned by piston 17 to frequency f_2 .

When the incoming radio wave is of the frequency f_1 the intensity of the magnetic field in resonant chamber 14 will be greater than that of the magnetic field in resonant chamber 15 since this is the resonant frequency of 14. There will consequently be a greater voltage induced in loop 22 than in loop 23 and a greater rectified voltage developed across output resistor 26 than resistor 27. Under this condition the end 31 of resistor 26 will be at its maximum potential with respect to the junction point 28. As the frequency of the incoming wave increases the magnetic field strength in wave guide 15 will increase, while that in the wave guide 14 will decrease. When the frequency of the wave reaches f_2 the intensity of the magnetic field in wave guide 15 will be a maximum since wave guide 15 is resonant at this frequency. The detected output voltages will then be such that the voltage across resistor 27 is a maximum and that across resistor 26 a minimum. If the crystal element 24 has been so connected that the end 31 of resistor 26 is positive with respect to the junction point 28, then the crystal element 25 should be so connected that the end 33 of resistor 27 is also positive with respect to junction 28. Thus, with respect to an output circuit connected to the terminal points 31 and 33, the load resistors 26 and 27 are in differential relation, i. e., in opposing relation. The two secondary wave guide circuit are preferably designed to have similar response characteristics, so that when the incoming wave is of frequency f_0 , equal voltages are developed across resistors 26 and 27. Since the voltages across these two resistors are in opposition the total output voltage developed will then be zero. A typical response curve 10 of the circuit of this invention is shown in Fig. 3.

The output voltage or voltages of the circuit of Fig. 2 may be applied by any of the conventional

methods to a signal utilization means. For example, the voltage between points 31 and 33 may be applied to a conventional single sided audio amplifier, or with junction point 28 grounded the potentials developed at 31 and 33 may be applied to a push-pull audio amplifier stage.

In one physical embodiment of the invention, the diameter of the coupling holes 18 and 19 was made approximately equal to one-fourth of the width of the broad side of the wave guide.

While the invention has been described with reference to a particular embodiment, it will be apparent to those familiar with the art that various changes and modifications may be made in the circuit as described and illustrated without deviating from the spirit and scope of the invention as defined by the appended claims.

I claim:

1. A frequency discriminator for detecting frequency deviations in hyper frequency carrier waves, comprising a primary cavity resonant at the center frequency of said carrier wave, a first secondary cavity resonant at a predetermined frequency above said center frequency, coupling means between said primary cavity and said secondary cavity, a second secondary cavity resonant at a predetermined frequency below said center frequency, coupling means between said primary

cavity and said second secondary cavity, a first non-linear circuit element responsive to the wave intensity in said first secondary cavity, a second non-linear circuit element responsive to the wave intensity in said second secondary cavity, and an output circuit connecting said non-linear circuit elements in differential relation for establishing a detected signal whose magnitude is proportional to the deviation of said carrier wave from said center frequency.

2. A frequency discriminator as claimed in claim 1, wherein said primary cavity comprises a wave guide closed at one end, said first secondary cavity comprises a wave guide whose length is substantially an integral number of half wave lengths at said first-named predetermined frequency, and said second secondary cavity comprises a wave guide whose length is substantially an integral number of half wave lengths at said second-named predetermined frequency.

3. A frequency discriminator as claimed in claim 1, wherein all of said cavities are constructed in the form of hollow wave guides, and wherein the coupling between said guides is inductive, and is provided by means of iris openings between said primary and secondary cavities.

ROBERT T. BENWARE.
